UNITED STATES PATENT OFFICE.

MEDOREM W. GREER, OF NEW YORK, N. Y., ASSIGNOR, BY MESNE ASSIGNMENTS, TO EVER-LAST COTTON SHOE CORPORATION, A CORPORATION OF NEW YORK.

SHOE CONSTRUCTION.

1,230,478.

Specification of Letters Patent.

Patented June 19, 1917.

Application filed August 21, 1915. Serial No. 46,593.

To all whom it may concern:

Be it known that I, MEDOREM W. GREER, a citizen of the United States, and a resident of the borough of Manhattan, city, 5 county, and State of New York, have invented certain new and useful Improvements in Shoe Construction, of which the following, taken in connection with the accompanying drawings, is a specification.

10 My invention relates to foot wear, more particularly such as is provided with a matted or woven fabric outer sole, and its object is to produce a construction in which the peripheral edges of the shoe sole are protected and covered by a curtain attached to 15 said edges and extending downwardly there-over to the wearing surface of the sole. Other objects of my invention will be specifically pointed out or will otherwise appear in 20 connection with the following description of the embodiment of my invention shown in the accompanying drawings in which Figure 1 is a vertical cross section through the forward portion of a shoe provided with a form 25 of my invention, Fig. 2 is a bottom view of the shoe shown in Fig. 1, Fig. 3 is an enlarged detail showing the shoe welt in position to be sewed to the outer sole and Fig. 30 4 is a similar detail showing the welt stitched to the sole.

The shoe illustrated consists of an upper 5, an inner sole 6 and a welt 7, the inner sole being channeled or lipped and the three parts mentioned being sewed together in the 35 usual method employed in the making of Goodyear welt shoes. The parts of the shoe not shown are subjected to the usual operations and finished in the usual manner.

The outer sole 8 may be of any suitable 40 material but preferably, as shown, it consists of a felted or a woven fabric such as heavy cotton-duck. This fabric sole may comprise several layers as 8 and 8^a which are cemented together by the use of a suitable 45 adhesive material, a close and tenacious adherence of the layers being produced by pressure. The innermost layer may also be cemented to the inner sole, and around its upper peripheral portions, if desired, to the 50 welt 7.

The vertical edges of a cotton-duck sole such as has been described fray out during the wear of the shoe and present an un-sightly appearance. Furthermore, such 55 edges cannot successfully be finished off in

such a manner as to produce a smooth, finished appearance which will not become rough and fuzzy when the shoe has been worn. In accordance with my invention, a finished appearance for the peripheral edge 60 of the sole, particularly of a fabric sole, is accomplished by providing a curtain 9 of suitable material which is secured to and extends around said edge so as to cover and protect the same. This curtain, as shown, 65 consists of a downwardly bent portion of the leather welt 7, which welt is wider than that used in the ordinary construction so that sufficient welt leather is provided beyond the outer sole periphery to form a curtain 9 when bent down over the outer sole edge. 70

The lower edge of this curtain extends substantially flush with the wearing or tread surface of the sole and the curtain is tightly 75 secured to the outer sole with the visible surface of the curtain substantially vertical. The securing together of the curtain and the sole may be accomplished in various ways, as by cement or by the employment of double 80 pointed tacks. Preferably, however, the curtain and outer sole are secured together by the stitching 10 which extends from the channel 11 in the curtain diagonally downward through the sole. This stitching may 85 extend through one or more layers of the fabric, but it is advantageous to so direct the stitching that it passes through only one layer. Preferably, the stitching of the welt and sole together is performed before the 90 last sole layer has been applied, in which case the curtain is designed to extend one layer's thickness below the lowermost stitched layer. When thus stitched the last sole layer is cemented in place, thus produc- 95 ing the construction illustrated, this last layer serving to cover the sole stitches and fitting within the curtain, its lower surface being substantially flush with the lower surface of the curtain. When the surface sole 100 layer has become worn, it may be removed and replaced by a new layer without disturbing the original stitching. The channel 11 in the curtain is, of course, tooled over, and thus made invisible, after the sewing operation has been completed. 105

I claim:—

1. In a shoe, the combination of an outer sole comprising superposed layers with a curtain covering the peripheral edge of such 110

outer sole, the lower edge of said curtain being substantially flush with the wearing surface of said sole.

2. In a shoe, the combination of an outer sole comprising superposed layers, with a curtain covering and bearing against the peripheral edge of said outer sole, the lower edge of said curtain being substantially flush with the wearing surface of said sole.

10 3. In a shoe, the combination of an inner sole, upper and outer sole, and a welt bearing against said upper and the upper surface of said outer sole and having a downwardly extending curtain covering the peripheral edge of said outer sole.

4. In a shoe, the combination of an outer sole comprising superposed layers of fabric secured together, with a curtain secured to and covering and bearing against the peripheral edge of said outer sole, the lower edge of said curtain being substantially flush with the wearing surface of said sole.

5. In a shoe, the combination of an outer sole with a curtain covering the peripheral edge of said outer sole and secured thereto by stitching, said stitching extending diagonally downward through the curtain and the sole.

6. In a shoe, the combination of an outer sole comprising superposed layers of fabric secured together, with a curtain covering the peripheral edge of said outer sole and secured thereto by stitching, said stitching extending diagonally downward through the curtain and the sole.

7. In a shoe, the combination of an inner sole, upper, and welt with an outer sole, said welt being provided with a vertical downwardly extending curtain portion, said

curtain being secured to, covering and bearing against the peripheral edge of said outer sole, and the lower edge of said curtain portion being substantially flush with the tread surface of said sole.

8. In a shoe, the combination of an inner sole, upper, and welt with an outer sole comprising superposed layers of fabric secured together, said welt being provided with a downwardly extending curtain portion, said curtain portion being secured to and covering the peripheral edge of said outer sole, and the lower edge of said curtain portion being substantially flush with the tread surface of said sole.

9. In a shoe, the combination of an inner sole, upper, and welt with an outer sole, comprising superposed layers of fabric secured together, said welt being provided with a downwardly extending curtain portion, said curtain portion covering the peripheral edge of said outer sole and secured thereto by stitching, said stitching extending diagonally downward through the curtain portion and the sole.

10. In a shoe, the combination of an inner sole, upper, and welt with an outer sole, comprising superposed layers of fabric secured together, said welt being provided with a downwardly extending curtain portion, said curtain portion covering the peripheral edge of said outer sole and secured to one of the layers thereof, said stitching extending diagonally downward through the curtain portion and said layer.

In testimony whereof, I have hereunto set my hand.

MEDOREM W. GREER.
